DISPLAY BOARD

Folke G. H. Engstrom, Rockford, Ill., assignor to
 American Cabinet Hardware Corporation,
 Rockford, Ill., a corporation of Illinois

Application June 20, 1941, Serial No. 398,896

4 Claims. (Cl. 35—50)

The invention relates generally to display boards and more particularly to a display board for use with items of which color is a feature in the selection thereof.

The general object of the invention is to provide a display board on which may be mounted articles of different colors to determine what background colors may be fittingly used with the respective colors of the articles.

More specifically, it is an object to provide a display board on which may be mounted articles provided with color, such as cabinet hardware, and which is so constructed that different colors may be positioned so as to selectively form a background for the articles, to illustrate the decorative effect of the combinations of the colors of the articles and the backgrounds and thereby facilitate selection of such combinations.

Another object is to provide a display board having means for supporting a plurality of articles, such as items of cabinet hardware, such items being similar but of different colors, and having a structure permitting insertion of different colored backgrounds for the articles, to facilitate selection of combinations thereof, the backgrounds carrying indicia to show recommended combinations.

Other objects and advantages will become apparent from the following description, taken in connection with the accompanying drawing:

Figure 1 is a perspective view of a display board embodying the features of the invention.

Fig. 2 is a side view of the board shown in Fig. 1.

Fig. 3 is a vertical sectional view taken on the line 3—3 of Fig. 1.

Fig. 4 is a horizontal sectional view taken on the line 4—4 of Fig. 1.

Fig. 5 is a view on a reduced scale of parts of the device.

When a buyer selects an article for use in the home, which involves a question of color, it is desirable to be able to show him how the color of such article will look in combination with other colors. One instance where a combination of two colors is frequently used is in the decoration of modern kitchens. In such decoration there will usually be a background color and a color used in the trim. The color used in the trim is frequently used in the hardware mounted on such articles of kitchen furniture as the cabinets. As an example, the drawer and door pulls for such cabinets may comprise chiefly chromium plated metal but may also have colored parts such as stripes or panels or colored plastic inserts. It is of course desirable that the color of the cabinet produce a pleasing combination with the color in such drawer pulls, since the latter will be seen with the color of the cabinet itself as a background.

A device embodying the features of the invention is designed to facilitate the selection of a combination of colors, and particularly the selection of the color used in the hardware to 5 combine with various background colors. Thus the device comprises generally a base on which may be supported samples of a hardware article, such as a drawer pull, in all the various colors in which it is regularly manufactured. The 10 drawer pulls are so supported on the board that sheets of the different background colors may be selectively placed in back of the articles so that the buyer can see the exact effect of the various color combinations. To this end the 15 articles are secured to a transparent pane so mounted on the board that a pocket is provided behind the pane. Into this pocket may be inserted sheets having the background color.

To further assist the buyer in the selection 20 of color combinations, means is provided for indicating what combinations are recommended by authorities on interior decoration. For this purpose, the sheets of background color carry indicia which, when the sheet is in place behind 25 the transparent pane, are aligned with the respective articles making a recommended combination.

The preferred embodiment of the invention 30 illustrated in the drawing comprises a base 10 in the form of a flat board. Preferably the base is adapted to be supported in the manner of an easel and for this purpose a wire bail or support 11 is pivotally secured by clips 12 to the rear of the board.

Means is provided on the front face of the 35 board for supporting the differently colored articles and the sheets having the background colors so that the two may be seen in juxtaposition. In the present instance, by way of illustration, the hardware article herein shown is a drawer pull comprising a bowed strip of metal 40 13 (see Figs. 3 and 4) having a plurality of longitudinal grooves 14 in its front face. The metal strip 13 is preferably chromium plated, while the grooves are suitably colored by means of 45 enamel. At the ends of the strip 13 are plastic inserts 15 of the same color as the enamel in the grooves. The colors utilized on such articles are usually standardized and are herein indicated in Fig. 1 by the symbols for ivory, yellow, green, 50 blue, red, and black.

The symbols of the articles having the various colors are mounted on the board in such a manner that the background colors may be placed behind them to permit their effect to be noted. 55 To this end, the six samples of pulls are mounted on a transparent pane 16 such as a piece of lucite. The pane is supported on the board in slightly spaced relation thereto so that the sheets of background color, here indicated at 17, may be 60 selectively inserted between the board and the

pane. To this end I provide parallel spaced guide members to permanently retain the pane 16 in place and to provide a pocket in which the colored background sheets 17 may be selectively inserted. In their preferred form each parallel guide member comprises an outer channel 20 (see Fig. 4) and an inner channel 21, the latter being of less width than the outer channel and being positioned therein. The channels on one side are positioned to face the channels on the other side. The rear flanges of the inner and outer channels are longer than the front flanges and are secured flatwise to the board as by screws 22. The space within the outer channels but in front of the inner channels is utilized to receive and hold the side edges of the transparent pane 16, while the sheets 17 are adapted to be inserted with their side edges in the inner channels 21.

Both the pane 16 and the sheets 17 are supported at the bottom preferably by tabs 23 integral with and bent forwardly from the rear flanges of the outer channels 20. The transparent pane 16 with the drawer pulls are held rigidly and permanently in place. To this end the front flanges of the outer channels 20 are provided with tabs 24 bent over the upper edge of the pane 16.

The pocket formed by the inner channels 21 behind the pane 16 to receive the sheets 17 is of such size that several sheets may be held therein at a time. However, it is of course only the front sheet that is visible through the pane as a background for the articles. The inner channels 21 are open at their upper end so that the sheets 17 may be readily withdrawn and shifted. To facilitate insertion of the sheets, the rear flange of the inner channel 21 extends upwardly beyond the outer flange a short distance and is bent rearwardly at an angle, as at 25 (see Fig. 3), to assist in guiding the sheets 17 into the channel. In order to hold the sheets tight against the pane 16, a comparatively flat leaf spring is secured to the board as by a screw 26 near the lower end of the sheets. The leaf spring thus presses the sheets forwardly flat against the pane 16.

Another feature of the invention resides in the provision of means to facilitate selection of color combinations by indicating which of the colors of the articles are recommended for use with the various background colors, such recommendations being those of authorities in decorating. To this end each sheet 17 is provided with indicia so located as to be positioned adjacent the different colored handles with which the particular background color is suitable. In the present instance, the handles are vertically aligned and are spaced a short distance from one of the side guide members. Each sheet is provided with indicia in the form of stars 27 which when the sheet is in place appear in the space between the articles and the side guide. Thus, in the illustration in the drawing, the first or front sheet shown is white, and stars are printed thereon so as to be visible at the side of all of the drawer pulls except the ivory colored pull. In other words, a white background is recommended as suitable for use with yellow, green, blue, red, or black drawer pulls but not with the ivory colored pull.

The sheets are also provided with small tabs 28 at their tops differently located on the respective

cards in the manner of index tabs, so that any particular color of sheet may be readily withdrawn and reinserted in the front of the pocket. When so inserted the stars 27 are located properly relative to the different drawer pulls.

From the foregoing, it will be apparent that I have provided a display board on which may be mounted items of different colors to facilitate selection of suitable background color for use with 10 respective items. The background colors are carried on sheets positioned, when the board is viewed from the front, so that each article is seen with a background of the given color. Thus a buyer may readily select the color of the item 15 which he desires to use with a given background color, or he may select a combination of colors for the background and the article. The stars on the respective sheets give the buyer a suggestion of what an authority on matters of color considers to be best.

I claim as my invention:

1. A device of the character described comprising, in combination, a base, a pair of laterally spaced members each providing a pair of channels facing toward the channels of the opposite member, a transparent pane mounted and permanently retained in the front channels, a plurality of differently colored articles mounted on said pane, and a plurality of differently colored sheets slidably mounted in the rear channels whereby the sheet at the front may be viewed as a background for the articles.

2. A device of the character described comprising, in combination, a base, a first pair of laterally spaced channels mounted on the base to face each other, a second pair of channels mounted within the first pair but of lesser width than said first pair, a transparent pane rigidly mounted in the space in the first pair alongside 35 the second pair, a plurality of differently colored articles mounted on said pane, and a plurality of differently colored sheets slidably mounted in the second pair of channels whereby the sheet adjacent the pane may be viewed as a background for the articles.

3. A device of the character described comprising, in combination, a base, a transparent pane, means for supporting said pane in slightly spaced relation to the base, a plurality of differently colored articles mounted on said pane, a plurality of differently colored sheets slidably inserted between said base and said pane whereby the sheet adjacent the pane may be viewed as a background for said articles, and resilient means 55 tending to hold said sheets flat against said pane.

4. A device of the character described comprising, in combination, a base, a transparent pane mounted on said base, a plurality of articles differently colored but otherwise identical mounted in alignment on said pane, a plurality of differently colored sheets removably supported by said base in back of said pane to selectively serve as a background for said articles, and indicia on the respective sheets located so as to be visible through said pane at the side of certain of said articles to designate the various article colors which are recommended for use with the particular background color.

CERTIFICATE OF CORRECTION.

Patent No. 2,312,532.

March 2, 1943.

• FOLKE G. H. ENGSTROM.

It is hereby certified that the name of the assignee in the above numbered patent was erroneously described and specified as "American Cabinet Hardware Corporation" whereas said name should have been described and specified as --American Cabinet Hardware Corporation, Rockford, Illinois, of Rockford, Illinois, a corporation of Illinois--, as shown by the record of assignments in this office; and that the said Letters Patent should be read with this correction therein that the same may conform to the record of the case in the Patent Office.

Signed and sealed this 18th day of May, A. D. 1943.

(Seal)

Henry Van Arsdale,
Acting Commissioner of Patents.
